(57) **CLAIM**

An ornamental design for a foot sleeve with bunionette cushion, as shown and described.

DESCRIPTION

FIG. 1 is a perspective view of a foot sleeve with bunionette cushion showing my new design in condition of use on a human foot;

FIG. 2 is a front view of my new design;

FIG. 3 is a top view thereof;

FIG. 4 is a right side view thereof;

FIG. 5 is a rear view thereof;

FIG. 6 is a left side view thereof; and,

FIG. 7 is a bottom view thereof.

The broken line showings of FIGS. 1-7 illustrate portions of the foot sleeve with bunionette cushion and environmental structure which form no part of the claimed design. Applicant also makes no claim to the interior surfaces of the sleeve. Contour lines are provided merely to illustrate contours of the material, and also form no part of the claimed design.
